(57) **CLAIM**

The ornamental design for a container for holding and transporting goods, as shown and described.

DESCRIPTION

FIG. 1 is a frontal perspective view of container for holding and transporting goods showing our design;

FIG. 2 is a front elevation view thereof;

FIG. 3 is a left side view thereof;

FIG. 4 is a top view thereof;

FIG. 5 is a bottom plan view thereof;

FIG. 6 is a rear elevation view thereof;

FIG. 7 is a right side elevation view thereof illustrating a tray of the container in raised position; and,

FIG. 8 is a rear perspective view thereof.

The broken line showings of upright handles, wheels and a pivoted wheeled platform in FIGS. 3 and 8 are for illustrative purposes only and form no part of the claimed invention.
